UNITED STATES PATENT OFFICE.

FRANCIS W. SHILLITTO, OF WEST HAVEN, CONNECTICUT, ASSIGNOR TO THE AMERICAN BUCKLE AND CARTRIDGE COMPANY, OF SAME PLACE.

DESIGN FOR A SUSPENDER-RING.

SPECIFICATION forming part of Design No. 21,860, dated September 20, 1892.

Application filed August 22, 1892. Serial No. 443,801. Term of patent 3½ years.

To all whom it may concern:

Be it known that I, FRANCIS W. SHILLITTO, of West Haven, in the county of New Haven and State of Connecticut, have invented a new Design for Suspender-Rings; and I do hereby declare the following, when taken in connection with accompanying drawing and the letters of reference marked thereon, to be a full, clear, and exact description of the same, and which said drawing constitutes part of this specification, and represents a face view of a suspender-ring.

This invention relates to a design for suspender-rings; and the design consists in the configuration shown in the accompanying illustration.

The upper end A and the banded lower end A' of the ring are straight and parallel with each other. The sides of the ring correspond to each other, and each is composed of an inwardly-curved upper portion B, diverging from the vertical center of the ring, and a shorter lower portion B', forming an acute

angle, or an angle less than a right angle, with the lower end of the upper portion B, converging toward the said center of the ring and forming an obtuse angle with the straight lower end thereof, the upper end of the inwardly-curved upper portion of the ring forming, substantially, a right angle with the straight upper end thereof. Taken as a whole, the ring may be said to represent in its general outline an ordinary flaring-mouthed bell.

What I claim as my invention, and desire to secure by Letters Patent, is—

The design for a suspender-ring, as herein described, and shown in the accompanying illustration.

In testimony whereof I have signed this specification in the presence of two subscribing witnesses.

FRANCIS W. SHILLITTO.
